Int. Cl. D8—02

U.S. Cl. D37—1

FIG. 1

FIG. 2

FIG. 3

FIGURE 1 is a perspective view of one side of the concavo-convex triangular file of this invention.

FIG. 2 is a perspective view from the opposite side thereof.

FIG. 3 is an enlarged end elevational view thereof.

The incomplete showing of the external surfaces of the concavo-convex triangular file is understood to be representative of a conventional abrasive surface as best shown in FIG. 3.

We claim:

The ornamental design for a concavo-convex triangular file, substantially as shown and described.
